UNITED STATES PATENT OFFICE.

ERNST GUSTAV HOFFMANN, OF NEW ROCHELLE, NEW YORK.

GRINDING BALLS.

No. 868,926.

Specification of Letters Patent.

Patented Oct. 22, 1907.

Application filed June 5, 1907. Serial No. 377,316.

To all whom it may concern:

Be it known that I, ERNST GUSTAV HOFFMANN, a citizen of the United States, residing in the city of New Rochelle, in the State of New York, have invented 5 certain new and useful Improvements in Grinding Balls, of which the following is a specification, reference being had to the accompanying drawing, forming a part hereof.

The grinding of metal balls for ball bearings and other purposes for which accuracy, uniformity and high finish are desirable, is commonly effected in a machine which comprises two disk-like plates of metal, relatively rotatable and pressed yieldingly, one toward the other, concentric grooves being formed in the adjacent 10 faces of the plates or in the face of one of them in which the balls are received together with an abrasive powder, usually emery powder, mixed with oil. The peripheral speed of the balls in such machines is not the same as the peripheral speed of the portions of the plate or 15 plates against which they are pressed, so that the loose particles of abrasive material between the balls and such portions of the plates are in this manner enabled to act upon the surfaces of the balls. The portion of 20 the ball which is thus removed by a particle of the abrasive material is almost infinitesimal, but each particle of abrasive material nevertheless makes upon the 25 surface of the ball a scratch, the character of which is dependent upon the size and character of the particle. The whole surface of the finished ball, therefore, is 30 made up of a vast number of scratches which are sometimes visible to the naked eye as a sort of cloudiness or dullness upon the surface of the ball and are always plainly apparent when the ball is examined with a microscope of moderate power. The balls finished in this 35 manner therefore leave something to be desired in the way of smoothness and by the present invention it has been discovered that a much greater approach to perfect smoothness of surface, as well as almost mathematically perfect sphericity and accuracy of the balls 40 can be secured by dispensing altogether with the use of loose abrasive material and by carrying on the grinding between two disks or plates, relatively rotatable and one or the other provided with concentric grooves as before, while one of such disks or plates is itself composed of abrasive material. Especially good results 45 are attained if such particles of abrasive material as may be loosened from the plate or disk as it wears away are immediately removed, as by washing them out with a constant and ample flow of a suitable liquid.

The invention will be more fully explained herein-
after with reference to the accompanying drawing in
which is represented so much of a grinding machine as
is necessary to enable the invention to be understood,
and in which

Figure 1 is a view in side elevation, partly broken

out, of a portion of such a machine, and Fig. 2 is a top view of the same.

In the particular form of mechanism which is chosen for illustration of the nature of the invention a stationary disk A, preferably of metal and having in its working face a series of concentric grooves a, is mounted upon a stationary shaft B, being held from rotation thereon and also from longitudinal movement by any suitable means, such as a pin b passing through the hub of the grinding disk or plate A and the shaft and removable to 60 permit the disk or plate to be moved back upon the shaft when necessary. A rotating disk or plate C, made of any suitable abrasive material, such as corundum, for example, is mounted to rotate upon the shaft B, being provided for this purpose, in the machine shown, with 65 a suitable wheel or belt pulley D. It is pressed toward the plate or disk A by any suitable means, as a stiff, spiral spring E surrounding the shaft B and abutting against an adjustable nut e. The plate or disk C may or may not be provided, when new, with concentric 70 grooves in its working face, which correspond to the grooves a in the working face of the disk or plate A, but such grooves are naturally formed therein as the use of the machine continues and are necessary to the proper action upon the balls, which depends upon the 75 different peripheral speeds of different portions of the balls in contact with the sides of the grooves.

The balls to be ground, which are shown in place in Fig. 1, may be introduced and removed and interchanged through slots in the disk A and by means of a 80 table G in spiral form, all as fully explained in Letters Patent of the United States No. 803,164, dated October 31, 1905, or by any other suitable means. The operation of the machine shown in the drawing is in general 85 the same as that of the machine described in said Letters Patent, but no emery powder or other loose abrasive material is supplied to the machine, the abrasive action of the disk C being alone relied upon. If this disk is made of suitable material, it will slowly wear away in an impalpable powder, but to prevent any 90 scratching of the balls by particles which may be loosened from the disk it is desirable that they be removed immediately. If the grinding should be done dry, such loose particles would be quickly thrown out or might be blown out by a blast of air suitably directed. 95 The grinding, however, is preferably carried on with a suitable liquid, kerosene oil being found to be well adapted for the purpose, and in order that all loose particles of abrasive material may be immediately removed, a somewhat copious flow of the liquid is main- 100 tained throughout the operation.

As shown in the drawing the working parts of the machine are mounted over a tank or reservoir H into which the oil or other liquid falls from the grinding disks and in which the particles of abrasive material and steel 110

- are precipitated. From the tank H the oil flows through a pipe h to a centrifugal pump I by which it is returned to the grinding disks through a pipe i by which the oil or other liquid is distributed upon the table G from which it passes with the balls through the disk A to the grinding surfaces. By such means the particles of metal and of abrasive material are immediately removed from the grinding surfaces and the scratching of the balls thereby is wholly obviated.
- 10 While the machine herein shown is well adapted for carrying out the invention, it will, nevertheless, be understood that the invention is not restricted to any particular form or type of machine and that the mechanism shown and described herein can be varied as may be found desirable to meet the necessities of different uses.

I claim as my invention:

1. A machine for grinding balls comprising two relatively rotating disks having parallel working faces with concentric grooves therein adapted to receive the balls between them, one of said disks being formed of abrasive material.
2. A machine for grinding balls comprising two, relatively rotating disks mounted upon a horizontal axis and having parallel working faces with concentric grooves therein adapted to receive the balls between them, one of said disks being formed of abrasive material.
- 25 3. A machine for grinding balls comprising a metal disk having concentric grooves adapted to receive the balls

and a disk of abrasive material, also having concentric grooves in its working face adapted to receive the balls therein, one of said disks being rotated with respect to the other.

4. A machine for grinding balls comprising two relatively rotating disks having parallel working faces with concentric grooves therein adapted to receive the balls between them, one of said disks being formed of abrasive material, and means to remove immediately the loosened abrasive material.

5. A machine for grinding balls comprising two relatively rotating disks having parallel working faces with concentric grooves therein adapted to receive the balls between them, one of said disks being formed of abrasive material, and means to discharge a stream of liquid between the disks throughout the operation to wash out the loosened particles of abrasive material.

45 6. A machine for grinding balls comprising two relatively rotated disks having parallel working faces with concentric grooves therein adapted to receive the balls between them, one of said disks being formed of abrasive material, a pump, connections to discharge liquid from the pump upon the working faces of the disks to wash out the loosened particles of abrasive material, a tank to receive the liquid from the disks, and connections to return the liquid from the tank to the pump.

This specification signed and witnessed this 3d day of 55 June, A. D., 1907.

ERNST GUSTAV HOFFMANN.
